REELING APPARATUS

Myles Morgan, Worcester, Mass., assignor to Morgan Construction Company, Worcester, Mass., a corporation of Massachusetts

Filed Nov. 27, 1957, Ser. No. 699,314

4 Claims. (Cl. 242—81)

This invention relates to a reeling apparatus and more particularly to apparatus arranged to coil the product of a rolling mill or the like.

In steel mill practice, it is common to coil the product of a rolling mill in a so-called "pouring" reel. In this type of reel, the product, such as rod, is projected into a lane between two concentric rows of reeling pins, and these rows of pins are rotated about their common center so that the rod is formed into a coil. In the past, the rod has been projected between the pins by means of a guide or pipe which extended through the wall of the reel on a level somewhat above the tops of the pins, particularly of the outer row of pins, with the angle of the pipe such that an imaginary extension lies between the pins. In this type of reel, however, the coil is discharged by raising a coil plate to the level of the top of the housing, the pins remaining behind. Because of this, it has been necessary that the rod pipe extend into the housing only a short distance, otherwise it would interfere with the upward movement of the coil plate during the discharge of the coil. Because of the considerable distance, then, between the end of the rod pipe and the annular space between the concentric rows of pins in which the coil was to be laid, it could not be said that the rod is positively guided into place. One difficulty commonly experienced because of this is that the rod has a tendency to climb upwardly along the inner pins, particularly at the end of a rod. This is because, during the passage of the front of the rod into the reel, the rear end of the rod is still in the mill and the rod is pushed; however, when the rear end of the rod is entering the reel there is no pushing action from the mill and the reel must act as a capstan to draw the rod through the apparatus. At times, therefore, there is considerable tension in the rod and this, combined with the high angle of approach of the rod through the pipe causes the rod to climb upwardly on the inner pins. This upwardly climbing not only causes a poorly formed coil, but also presents the danger that the rod may feed upwardly on the inner pins and go over the top of the pins. These and other difficulties experienced with the prior art devices have been obviated in a novel manner by the present invention.

It is, therefore, an outstanding object of the present invention to provide a reeling apparatus in which the entrance pipe is capable of movement from an operative position within the reel to an inoperative position entirely free of the reel.

It is another object of the present invention to provide a reeling device of the pouring type having inner and outer concentric rows of pins and an entrance pipe which may be moved during reeling to a position closely adjacent the inner row of pins.

A further object of this invention is the provision of a reeling apparatus for use in a rolling mill in which the capstan effect necessary to draw the tail end of a length of rolled product does not cause mis-coiling.

Another object of the present invention is the provision of apparatus for moving a guide pipe associated with a pouring reel from a position closely adjacent the inner pins during coiling to a position entirely exterior of the reel housing during discharge of the coil.

With these and other objects in view, as will be apparent to those skilled in the art, the invention resides

2

in the combination of parts set forth in the specification and covered by the claims appended hereto.

The character of the invention, however, may be best understood by reference to certain of its structural forms as illustrated by the accompanying drawings, in which:

FIGURE 1 is a plan view of a reeling apparatus embodying the principles of the present invention.

FIGURE 2 is a sectional elevational view of the reeling apparatus taken on the line II—II of FIGURE 1.

FIGURE 3 is a vertical sectional view of a portion of the apparatus taken on the line III—III of FIGURE 4, and

FIGURE 4 is an inclined sectional view of the apparatus shown in FIGURE 3, taken on the line IV—IV of FIGURE 3.

Referring first to FIGURES 1 and 2, wherein are best shown the general features of the invention, the reeling apparatus, indicated generally by the reference numeral 10, is shown in use with an output portion 11 of a rolling mill and a discharge conveyor 12. The level of the conveyor 12 is indicated by the dotted lines and the reference characters c—c in FIGURE 2. The reeling apparatus consists of a housing 13 of circular tubular conformation with a vertical axis, containing a drive plate 14 extending horizontally therethrough and having two rows of concentric pins 15 and 16 connected thereto. The upper edge of the housing 13 is on the same level c—c as the conveyor 12, and the inner pins 16 extend to this height also. The outer pins 15, however, are considerably shorter than the inner pins, as is evident in FIGURE 2. A coil plate 17 is slidable over the pins from a position at the level of the conveyor to a position closely adjacent to the drive plate 14. A shaft 18 is provided for the actuation of this member. A push-off arm 19 is pivotally mounted at 21 to the housing 13 in such a manner as to be swingable over the top of the housing at the level of the conveyor to sweep off coils. The end 11 of the rolling mill consists in a general way of a guide 22 suitably mounted on a support 23 and having an end which terminates in a junction box 24. Extending from the junction box 24 is a guide pipe 25 an end of which is adapted to be situated within the housing between the rows of pins 15 and 16, and this end is provided with a hardened steel nozzle 26. An actuator 27 is mounted externally of the housing 13 and acts to position the guide pipe 25.

Referring now to FIGURES 3 and 4, which best show the construction of the actuator 27, the guide pipe 25, and the junction box 24, it can be seen that the outer end of the guide pipe 25 is provided with an outwardly flared portion 28 which is aligned with the guide 22 of the rolling mill. A pivot pin 29 is welded to the outer surface of the flared portion 28 and extends through an aperture 31 in a hinge plate 32 welded to the inner surface of the junction box 24. A suitable opening 33 is made in the side of the junction box 24 to permit angular movement of the guide pipe 25 about the axis designed by the pin 29. An adapter block 34 is welded to the outer surface of the housing 13 adjacent the top edge thereof, and this block is provided with an inclined face 35 to which is fastened a supporting plate 36. The outwardly facing surface of the supporting plate 36 is provided with an abutment 37 to which is fastened one end of a linear hydraulic actuator 38, the other end of which has a piston rod 39 extending therefrom. The piston rod is suitably apertured and pivotally connected by a pin 39a to the ends of two levers 41 and 42 which have a common hinged connection to the piston rod. The other end of the link 42 is fastened to the supporting plate 36 by means of a pivot pin 49. The same end of the link 42 is provided with an actuating finger 44 for a use to be explained further hereinafter. A microswitch 45 is mounted on the

supporting plate 36 in such a position that its actuating finger may be contacted on occasion by the finger 44 of the link 42. The other end of the link 41 is connected by means of a pivot pin to one arm of a crank arm 43. The crank arm 43 is connected by means of a pivot pin 43a to the supporting plate 36. The other arm of the crank arm 43 is provided at its end with a slot 45a thus forming a bifurcation. The slot is slightly wider than the diameter of the guide pipe 25 and, as can be seen in FIGURE 4, the guide pipe always resides within this slot.

The supporting plate 36 is provided with an inclined upper edge 46 extending at an angle approximately 45 degrees to the horizontal. At one end of the edge 46 the supporting plate 36 is provided with abutments 47 having a hinge pin 48 which not only extends through the abutments 47, but also through a closure bar 49 so that the closure bar is capable of hinged movement about the axis of the pin 48. At the other end of the edge 46 the supporting plate 36 is provided with a bifurcation 51 between which may reside the other end of the closure bar 49. A pin 52 normally extends between the abutments to maintain the closure bar in place.

The edge 46 and the lower edge of the closure bar 49 together form a slot 53 extending at an angle of around 45 degrees to the horizontal. In FIGURE 3 it can be seen that the inclination of the supporting plate 36 to the horizontal is in the order of 60 degrees, the particular angle selected being such that the supporting plate 36 is at right angles to the guide pipe 25 when the free end of the guide pipe lies in its operative position between the two concentric rows of pins 15 and 16. It should be pointed out also that the pin 29 lies in a plane parallel to the supporting plate 36 at a right angle to the edge 46 of the supporting plate so that the guide pipe 45 is pivotally movable in a plane parallel to the edge 46 or in other words is movable within the slot 53.

The operation of the invention will now be readily understood in view of the above description. The rolled material, such as rod, arrives at the reeling apparatus through the guide 22 and passes through the guide pipe 25 into the space between the concentric rows of pins 15 and 16. The drive plate 14 is rotated carrying the pins 15 and 16 with it and this causes the wire to be coiled as it emerges from the guide pipe 25. When the back end of the rod arrives in the reel, the coil is complete and the shaft 18 is moved upwardly to carry the coil plate 17 and coil with it. The coil plate carries the coil and eventually arrives at the level of the conveyor 12. At this level the coil is also free of the housing 13 and the kick-off arm 19 moves across the top of the housing and pushes the coil laterally across the coil plate over the edge of the housing 13 on to the conveyor 12. It will be appreciated, however, that if the guide pipe 25 is left in the position shown in FIGURES 1 and 2 that the coil on the coil plate 17 will strike it. Interference in this manner between the coil and the guide pipe 25 may cause disruption of the coil and also prevent the coil from being moved off on to the conveyor by means of the pushoff arm 19. The actuator 27, therefore, is provided to assure that as the coil plate 17 rises vertically the guide pipe 25 is moved into a neutral position where it does not interfere with the coil or the coil plate. In order to do this oil is admitted into the linear actuator 38 so that the piston rod 39 emerges from its cylinder. This not only causes a rotative movement of the link 42 about the pivot pin 40, but also causes a counter-clockwise movement of the link 41 about the pivot pin by which it is connected to one end of the crank arm 43. Continued upward movement of the piston rod 39 causes the lower arm of the crank arm 43 to move to the right, and this, in turn, causes rotation of the crank arm about its pivot 43a, and a movement of the upper bifurcated arm of the crank arm to the left and upward. Movement of the crank arm in this manner causes movement of the guide pipe 25 along the edge 46 of the supporting plate within the slot 53.

Movement, of course, takes place about the axis of the pivot pin 29 within the junction box 24. The effect of this is that the inner end of the guide pipe 25 with its hardened nozzle 26 is moved at an angle of approximately 45 degrees upwardly and laterally. The pipe, therefore, comes to rest in the position shown in dotted lines in FIGURES 1 and 2. At that time the pipe resides in the upper part of the slot 53 and the finger 44 has contacted the microswitch which is connected in a manner not shown so as to terminate the flow of oil to the linear actuator 38.

During the coiling of the rod the end of the guide pipe 25 and its nozzle 26 lie well downwardly of the top of the housing 13 between the concentric rows of pins 15 and 16. Therefore, rod emerging from the nozzle is constrained to a position which is at least below the end of the nozzle 26. In other words, as the back end of the rod emerges from the rolling mill and the wheel begins to act as a capstan, it is not possible for the tension in the rod to cause the rod to move upwardly along the inner pins 16. The nozzle 26 in its lower position prohibits the movement which would otherwise take place, of the rod upwardly along the inner pins. Nevertheless, when it is desired to discharge a finished coil, the guide pipe and nozzle are moved well out of the reel into a position in which they will not interfere with the discharge of the coil.

It is obvious that minor changes may be made in the form and construction of the invention without departing from the material spirit thereof. It is not, however, desired to confine the invention to the exact form herein shown and described, but it is desired to include all such as properly come within the scope claimed.

The invention having been thus described to what as claimed as new and desired to secure by Letters Patent is:

1. A reeling apparatus for rod comprising a fixed tubular housing of circular cross-section, an inner and an outer row of pins mounted within the housing concentrically of the housing thereof for rotation about the axis of the housing, a guide pipe extending into the housing and having one end which resides in a first position between the rows of pins substantially below the upper ends of the inner row, a junction means to which the other end of the pipe is connected for angular movement relative to the housing in position to receive the rod, an actuator connected to move the guide pipe in a plane lying at an acute angle to the said axis, means restricting the movement of the pipe to the said plane, the actuator moving the pipe from the said first position to a second position wherein the said one end is entirely removed from between the rows of pins and substantially above their upper ends as well as outside an imaginary cylinder defined by the extensions of the outer row of pins.

2. A reeling apparatus for rod comprising an open-ended fixed housing of circular cross-section, an inner and an outer row of pins mounted within the housing concentrically of the housing for rotation about the axis of the housing, a guide pipe extending into the housing and having one end which resides in a first position between the rows of pins substantially below the upper ends of the inner row, means to which the other end of the guide pipe is connected for angular movement relative to the housing, an actuator connected to the intermediate portion of the guide pipe to move it in a plane lying at an acute angle to the said axis, means restricting the movement of the pipe to the said plane, the actuator moving the pipe from the said first position to a second position wherein the said one end is entirely removed from between the rows of pins and substantially above their upper ends as well as outside an imaginary cylinder defined by the extensions of the outer row of pins.

3. A reeling apparatus for rod comprising a vertical fixed housing of circular cross-section, an inner and an outer row of vertical pins mounted within the housing

concentrically of the axis thereof for rotation about the said axis, a guide pipe extending into the housing and having one end which resides in a first position between the rows of pins substantially below the upper ends of the inner row, means to which the other end of the guide pipe is connected for hinged movement relative to the housing, means defining a slot through which the guide pipe extends, the slot extending at a substantial angle to the horizontal, and an actuator connected to the intermediate portion of the guide pipe to move it in an inclined plane along the slot from the said first position to a second position wherein the said one end is entirely removed from between the rows of pins and substantially above their upper ends as well as outside an imaginary cylinder defined by the extensions of the outer row of pins.

4. Reeling apparatus comprising a fixed housing, two concentric circular rows of pins mounted within the housing for rotation about their common axis, a guide pipe extending into the housing and having one end which resides in a first position between an inner and

outer row of pins substantially below the upper ends of the inner row, the other end of the pipe being connected for angular movement of the pipe relative to the said housing, and an actuator capable of moving the guide pipe in a plane lying at an angle to the said axis from the said first position to a second position wherein the said one end is entirely removed from between the rows of pins and substantially raised above their upper ends and lies outside an imaginary cylinder defined by an extension of the outer row of pins and means restricting the movement of the pipe to the said plane.
